REAR VIEW MIRROR FOR MOTOR VEHICLES

John Anthony Day, Kinver, England, assignor to Desmo
Limited, Birmingham, England, a British company

Filed Nov. 26, 1965, Ser. No. 88,229

Claims priority, application Great Britain June 22, 1965

Term of patent 14 years

(Cl. D14—6)

FIG. 1.

FIG. 2.

FIG. 3.

FIG. 4.

FIGURE 1 is a side view of a rear view mirror for motor vehicles showing my new design;

FIGURE 2 is a front perspective view thereof;

FIGURE 3 is a rear view; and

FIGURE 4 is an underneath plan view.

I claim:

The ornamental design for a rear view mirror for motor vehicles, as shown.
